(57) **CLAIM**

The ornamental design for a tire tread, as shown and
described.

DESCRIPTION

FIG. 1 is a front perspective view of a tire tread showing our
new design;

FIG. 2 is a front view thereof;

FIG. 3 is a right side view thereof;

FIG. 4 is a left side view thereof;

FIG. 5 is a top plan view thereof;

FIG. 6 is a fragmentary enlarged front view thereof;

FIG. 7 is a cross-section view taken along line 7-7 in FIG.
6;

FIG. 8 is a cross-section view taken along line 8-8 in FIG.
6;

FIG. 9 is a cross-section view taken along line 9-9 in FIG.
6; and,

FIG. 10 is a cross-section view taken along line 10-10 in
FIG. 6.

Broken lines show environmental portions of a tire that are
not being claimed, and form no part of the claimed design.
The light stippled surface shading represents the surface of
the tire tread, and the dark stippled surface shading repre-
sents the recessed portion of the tread grooves, having the
depth as shown in FIGS. 7, 8, 9 and 10.
